UNITED STATES PATENT OFFICE.

HENRY COAKLEY, OF NEW YORK, N. Y.

AIRPLANE.

Application filed September 15, 1920. Serial No. 410,465.

To all whom it may concern:

Be it known that I, HENRY COAKLEY, a citizen of the United States, and resident of the borough of Manhattan, in the city, 5 county, and State of New York, have invented certain new and useful Improvements in Airplanes, of which the following is a specification.

This invention relates to airplanes and my 10 improvements are directed to certain arrangements of supporting elements in opposed and intersecting dihedral and reverse dihedral relationship, whereby increased structural strength is acquired with minimum weight and wherein also a maximum degree of sustentation and flying efficiency is achieved.

One of the objects of my invention is to minimize head resistance such as is produced 20 by struts used in connecting and bracing superposed wings, and to this end I cause the superposed wings themselves to be in intersecting relation, so that the separate wings are each an integral part of a unified 25 whole, and all stresses and strains, whether local or general, are distributed throughout the entire structure.

Further, the effect of the dihedral and reverse dihedral arrangement of the super- 30 posed wings is to cause said wings to constitute balancing couples, operating about the longitudinal axis of the airplane, thus supplying thereto a large measure of inherent lateral stability.

My invention further comprehends a 35 wing structure including a series of spaced, spanwise extending spars, which are arranged as to their depth and location to conform to the wing contour, and which 40 also, in the intersecting relation of the wings, comprise the connective elements thereof.

Also, in certain embodiments of my invention, where struts and wires are employed, these are stream-lined and arranged 45 in novel manners to intercommunicate the stresses through the structure.

Other features and advantages of my invention will hereinafter appear.

In the drawings:

50 Figure 1 is a front elevation of my improved airplane in a simple form thereof.

Fig. 2 is a section through the chord of a wing, showing spars arranged spanwise therein.

55 Fig. 3 is a front elevation of an airplane

wherein the connective wing spars are braced with stream-lined wires.

Fig. 4 is a front elevation of my improved airplane in a form wherein stream-lined struts are the bracing elements with the connective wing spars. 60

Fig. 5 is a front elevation of the airplane in a form wherein both stream-lined struts and wires comprise bracing elements with the connective wing spars. 65

Fig. 6 is a front elevation of my improved airplane in a form thereof wherein bracing occurs at the points of wing intersection, and also at intermediate points.

Fig. 7 is a front elevation of the airplane 70 in a form thereof wherein the bracing members are themselves braced by other intersecting brace members.

Fig. 8 is a front elevation of an airplane wherein strut and wire braces extend from 75 points intermediate the points of wing intersection.

Fig. 9 is a front elevation of an airplane wherein stream-lined struts, located at the points of wing intersection, are braced relatively to other points of wing intersection 80 by stream-lined wires, and

Figs. 10 and 11 are respectively front elevations of my improved airplane, showing small and large multiplanes with stream-lined braces. 85

The figures above noted are more or less diagrammatic in character, being intended for the purpose of indicating the inventive features involved, because the structure thus 90 represented will by aid of the following description be fully apparent to those skilled in the art:

Describing first the simple form of my invention shown in Fig. 1, the numeral 1 indicates a body portion, which may be a boat or fuselage, and is here shown as provided with wheels 2, for land use.

Extending from body 1, at opposite sides thereof, are the wings 3, 3, each at upward 100 angles, in dihedral form, and superposed wings 4, 4 are provided at opposite, downward angles respectively in intersecting relation with the wings 3, 3. The wings 4, 4 themselves intersect at their inner ends in the vertical, longitudinal plane of the airplane, and all of the wings are connected 105 at their points of intersection.

The unified structure of connected wings is rendered strong by reason of a certain 110

individual wing construction (see Fig. 2) wherein a series of parallel spars 5 are arranged in spaced relation, extending spanwise of the wing, and occurring relatively 5 to its chord, fore, aft, and in intermediate positions thereof. By this arrangement of spars, the number of ribs required in the wing construction may be materially reduced since the height of the spars, according 10 to their chordwise position in the wing, determines the contour of the latter, and the spars import strength into the wing structure to accord it lateral or spanwise stiffening.

15 In the relative arrangement of the dihedral wings 3, 3 with the wings 4, 4, the latter having reverse dihedral, the spars of said wings meet and are joined together by any suitable means, to provide a secure junction 20 between said wings at their points of intersection. So that practically said spars constitute an integral, angled framework for the whole wing fabric of the machine.

This, in effect, is an essential feature of 25 my invention, whether it be applied in the simple form of airplane shown in Fig. 1 or in more elaborate structures, such for example as are shown in the remaining figures of the drawings.

30 In Fig. 3 the structure of wings 6, 6, 7, 7, for instance, is amplified in strength by stream-lined wires 8; 9, 9; and 10, 10, the wire 8 extending from the vertex or intersecting points of wings 7, 7, and joining 35 with wires 9, 9, that engage with wings 6, 6, at points intermediate the respective spans thereof; said wires 9, 9 also joining with the wires 10, 10, that extend respectively to the vertices or intersecting points of the 40 wings 6, 7. Also spars 11 of the wings 6, 6, extend downwardly beyond their point of mutual intersection, to constitute the landing gear frame, and these spars 11 are braced together by streamlined wires 12, 45 and to the wings by streamlined wires 13.

In the example of Fig. 4, which provides a greater extent of wing surface, the lower, central, dihedral wings 14, 14, are intersected by the reverse dihedral wings 15, 15, 50 and in superposed relation with wings 15, 15, are the wings 16, 16; streamlined struts 17 being provided between the superposed wings and connected at the intersecting points, the connections occurring, as previously stated, in conjunction with the wing spars aforesaid.

While the number of wings employed may be varied, also the relative arrangements thereof, the essential characteristics 60 in the integral formation of the frame construction, wherein the wing spars of oppositely angled wings meet and are united at the points of intersection or vertices which they form, comprise the general structural 65 scheme whereby strength and rigidity are

given the entire fabric in all the different forms of airplane comprehended by my invention.

Thus, in Fig. 5, streamlined struts 18, and streamlined wires 19 constitute the 70 wing bracing elements, the spars of the central dihedral wings being extended, at 20, to comprise part of the water maneuvering chassis, having the floats 21.

In Fig. 6 another form of interbracing 75 by streamlined wires 22 is shown, also streamlined struts 23, which support the floats in conjunction with the wings and said wire bracing.

In Fig. 7 a modification is shown where-in the propelling means is suspended between wings by streamlined wire bracing, this feature also being exhibited, in varied forms, in Figs. 8, 9 and 10; while, in Fig. 11 the said wire suspension means is augmented by streamlined struts extended between the wing intersections.

Fundamentally, in the different forms of my invention illustrated, as in equivalent variations thereof, structural strength of 90 the airplane is achieved mainly by the interconnection of the angled wings one with another, the junction of the wing spars and the relative arrangement of said wings—as thus connected—being depended upon for the direct absorption of the main strains and stresses to which the machine is subjected in operation, and thereby the requirement for the employment of bracing struts and wires, or either, is largely diminished, with a consequent minimizing of head resistance presented by such bracing.

Also, the greater area of wing surface, at a relatively small lift-drift ratio, provided in my improved airplane construction, assures a high degree of flying efficiency.

With a proportionately large wing chord relatively to a large gap between the superposed wings, the drift is practically all downward, having the effect of an entirely vertical lift (or sustentation) exerted upon the wings. This latter effect only occurs with long spanwise wings at an appreciable dihedral angle relation when the wings 110 themselves are each intersected in dihedral angle relation (or are in parts which have reverse dihedral angle relation); otherwise a large portion of the aero-dynamical force upon the wings would be lost by part of 115 the drift upon one wing being compounded laterally against the drift upon the other wing. Therefore my improved airplane has by simple justa-construction large lift, low resistance, improved stability, light 120 weight, and great strength in the novel arrangements of its embodiments.

The external bracing means, with wires and struts, is important because, due to the novel form of bracing devised by me, its 130

objective is achieved with the use of a minimum quantity of material, both in wires and struts. Further, this bracing, both of wires and struts, engages with the 5 wing spars, both at the points of intersection between oppositely angled spars, and at intermediate points along some of the spars, for the purpose of dividing the 10 stresses and thus causing a more complete distribution thereof throughout the structure.

Variations within the spirit and scope of my invention are equally comprehended by the foreclosure disclosure.

15 I claim:—

1. An airplane having superposed supporting units, respectively angled and intersecting in dihedral and reverse dihedral relation, characterized by the central portion of a lower unit having dihedral angularity, and laterally extended portions of 20 said units having like symmetrical angularity.

2. An airplane having superposed supporting units, respectively angled and intersecting in dihedral and reverse dihedral relation, characterized by the central portion of a lower unit having dihedral angularity, and laterally extended portions of 25 said units having like symmetrical angularity, the spars of said units being engaged at their points of intersection, to constitute an integral formation for the entire airplane.

3. An airplane having lower dihedral, 30 and upper, reverse dihedral wings in opposed, intersecting relation, said wings each having a plurality of spars that are mutually engaged at their points of intersection, spars of said dihedral wings having 35 extensions which serve as supports for the landing gear.

Signed at the borough of Manhattan, in the city, county, and State of New York, this 7 day of September A. D. 1920.

HENRY COAKLEY.
